ATTORNEY.

UNITED STATES PATENT OFFICE.

THOMAS C. BARNUM, OF INDIANAPOLIS, INDIANA.

TAG.

SPECIFICATION forming part of Letters Patent No. 478,185, dated July 5, 1892.

Application filed July 6, 1891. Serial No. 398,576. (No model.)

To all whom it may concern:

Be it known that I, THOMAS C. BARNUM, a citizen of the United States, residing at Indianapolis, in the county of Marion and State of Indiana, have invented a new and useful Tag, of which the following is a specification.

My invention relates to an improvement in tags for marking trees and for other like purposes.

10 The object of my improvement is to provide a tag which is adapted to be secured to the limb of a tree or like object without the use of strings, wires, or like attaching devices.

15 The accompanying drawings illustrate my invention.

Figure 1 represents a plan of the blank from which the tag is formed when cut to shape preparatory to being folded. Fig. 2 is a plan of the complete tag. Fig. 3 is an edge view of 20 the same. Figs. 4, 5, and 6 illustrate the manner in which the tag is applied to the limb of the tree, being, respectively, a side elevation, a top view, and an edge view. Fig. 7 shows the tag in position on the limb of the tree. Fig. 8 is a plan of the tag having an auxiliary marking-strip attached thereto. Fig. 9 is an 25 edge view of the same. Fig. 10 is a plan of the auxiliary strip.

In the drawings, A designates an oblong 30 strip of paper or light sheet metal having near each end a perforation F.

B and C are like notches cut in diagonally-opposite corners of the blank, and D D are slits cut from the inner corners of the notches 35 to the perforations F F, respectively.

The blank having been cut in the manner above described and printed is folded upon itself lengthwise in such a manner that the holes F register with each other, and the 40 notches B and C are covered on opposite sides, as shown in Fig. 2. The opposite parts, except those embraced between the notches B and C, are secured together by cement or in any other suitable manner, and the tag is then 45 complete and ready for use. In applying the tag to a limb or to any other object not larger

in diameter than the holes F one of the notches B or C is brought opposite the limb, the limb resting against the exposed surface of the opposite fold and the overlapping parts G and H, which have not been fastened together, are then forced apart, as shown in Figs. 5 and 6, and the limb passes first into the opposite notch and then down into the openings F. The parts G and H then close together and 55 effectually prevent the accidental removal of the tag from the limb.

In the modification shown in Figs. 8, 9, and 10 the blank is provided with a narrow slot I at the line of folding, (indicated in dotted 60 lines in Fig. 1,) and a T-shaped strip J is thrust through this slot, and its arms are secured between the folds of the body of the tag, as clearly shown.

A tag is thus formed which may be cheaply 65 made and is quickly applied without the use of strings or wires.

I claim as my invention—

1. The above-described tag, consisting of an oblong strip of sheet material having near 70 each end a perforation F, notches B and C, cut in the ends near diagonally-opposite corners, and slits D D, connecting said notches respectively with said perforations, said strip being folded upon itself and its opposed parts 75 secured together, except between said notches, whereby a single structure is formed having a single central opening, and the free overlapping parts C and H, substantially as set forth.

2. In a tag, the combination, with the folded 80 strip having a pair of registering perforations, notches B and C, slits D D, connecting said perforations and notches, respectively, and the transverse slot I at the fold, of the auxiliary strip J, projecting through the slot and 85 secured in the fold of the strip, for the purpose set forth.

THOMAS C. BARNUM.
